UNITED STATES PATENT OFFICE

1,992,041

LIGHT PROJECTOR

Val J. Roper, Cleveland, and Willard C. Brown,
East Cleveland, Ohio, assignors to General
Electric Company, a corporation of New York

Application August 16, 1932, Serial No. 629,010

1 Claim. (Cl. 240—41)

Our invention relates to light projectors which comprise a reflector and a light source accurately disposed with reference to the surface of the said reflector. Such reflectors may be in the form of a surface of revolution such as a paraboloid, and with at least one focus; or they may have modified contour with an equivalent focus or with an optimum point for the light source. In order to obtain dependable results, the light source must be accurately located with reference to the said focus or optimum point. More especially our invention relates to ordinary vehicle headlamps. According to the prevailing practice such headlamps comprise a parabolic reflector or modified parabolic reflector and a socket which received an incandescent electric lamp. According to one practice, the socket is adjustable along the longitudinal axis of the reflector, and according to another practice, the socket is fixed with reference to the reflector. In both cases, however, the incandescent lamp is removable. In the former case reliance is placed upon the adjustment of the position of the socket and therefore of the lamp filament preliminarily by the manufacturer, and afterwards by the user of the car. In the latter case there is no opportunity for adjustment after the manufacture of the headlamp, and reliance is placed upon the uniformity of the incandescent lamp filament positioning by the incandescent lamp manufacturer, and also of course upon the accurate positioning of the socket with reference to the reflector by the headlamp manufacturer. One object of our invention is to provide means of securing more dependable results and to provide an effective and efficient method of manufacture of the device for securing such results.

Heretofore the filament has not always been positioned with reference to the focus of the reflector due either to inaccuracies of assembly of the socket with the reflector or, in some cases, to variations in position of the filament with reference to the base which is received in the socket. Inasmuch as the larger reflectors with the longer focal distances are less sensitive to inaccurate filament positioning, the tendency has been to make use of the larger reflectors. There are, however, advantages in the use of smaller reflectors inasmuch as it enables the use of more reflector and light source combinations and their effective disposition in the front of the vehicle. The increased flexibility in design gained by the use of the smaller reflectors is important not only from the standpoint of effective light distribution, but also because of such advantages as

lowered wind resistance and better appearance arising from the use of smaller headlamps. With such reflectors, single filament lamps may be used to better advantage than at present as more headlamps may be employed. Another object of our invention is the provision of a device which may comprise a small reflector with the position of the light source fixed so accurately that a beam of the correct dimensions and directions may always be secured.

According to our invention the reflector and electric lamp are fixedly united and in the process of their union the position of the light source is so fixed with reference to the reflector that a beam of the desired illumination and distribution is uniformly secured. The preferred form of our invention is that in which a portion of the reflector constitutes the base of the electric lamp. Other features and advantages of our invention will appear from the following description there- 10 of and from the accompanying drawing.

In the drawing Fig. 1 is a horizontal section through a reflector unit of our invention; Fig. 2 is a perspective diagrammatic view of apparatus employed in a method of definitely positioning 25 an electric lamp in a reflector; Fig. 3 is a vertical section of a projector utilizing two reflector units of our invention; Fig. 4 is a horizontal sectional view of a modification of said unit; and Fig. 5 is a vertical section through a projector utilizing 30 said modification.

Referring now to the drawing and more particularly to Fig. 1 thereof, our invention comprises a reflector 10, in this instance having a parabolic contour, with a flange 11 extending outward from 35 the rim thereof and with an opening at the apex thereof in which is mounted an incandescent lamp 12. The lamp 12 is supported in the desired location by a ring 13 of cement in a heel 14 extending rearwardly of the reflector. The cement 40 adheres to the inner surface of said heel and to the neck 15 of the lamp bulb. The said heel is preferably firmly attached to the back of the reflector by soldering or welding and supports by an inwardly extending flange an insulating plug 45 16 through which conductors 17 and 18 pass. Conductor 17 is attached within the shell to lead wire 19. The lead wires 18 and 19 pass inwardly through the stem press 20 into the interior of the lamp 12 and are each connected to an end of the 50 filament 21 mounted therein.

We prefer to use the method indicated in Fig. 2 for the adjustment of the lamp with reference to the reflector. This is performed while the cement 13 is still in a plastic state. The method 55

consists in covering the open end of the reflector with a shield 22 having a plurality of apertures 23 therein which allow a series of images of the filament to be thrown on screen 24. As illustrated, a parabolic reflector is used and the shield has a pair of apertures horizontally disposed, as well as a pair vertically disposed. The screen is marked with figures, rectangles 24' as shown, one for each aperture in the shield 22. These indicate the tolerance allowable for inaccuracy of filament position when the screen is positioned a definite distance from the lamp. Should the filament be located incorrectly to the left or right, the horizontally disposed pair of images will be out of position and so also will the vertically disposed pair of images should the lamp require adjustment vertically. Incorrect location along the axis of the reflector, that is, when the filament is ahead or behind proper position, causes both the horizontal and vertical pairs of images to be displaced. By suitably adjusting the position of the lamp, the images may be caused to fall each within the limits of a figure and the cement then allowed to harden. On account of the accuracy of this method it may be employed for very small reflectors of very short focal length which are exceptionally sensitive to improper filament position.

An application in which two of the reflector units of our invention are used is shown in Fig. 3. In this instance two reflector units are used in order to produce beams of different elevation such as are at present used in automotive lighting. The reflector is in each case fastened immovably by flange 11 and screws (not shown) to the projector housing 25 and is covered by lens 26. The current is supplied to the lamps through cords 17 each comprising a pair of insulated conductors and connected to a plug 27 which is inserted in connecting block 28 attached to the

housing. This is in turn connected to switching and battery equipment through cord 29.

The modification of our invention shown in Fig. 4 differs from the species just described in that the unit is constructed so as to be supported in the projector by heel 30. The heel is attached to the reflector 31 and cement 32 unites it to the neck of lamp bulb 33. The lamp filament 34 is definitely located with respect to the reflector and is connected to leading-in wires 35 and 36 which are in turn connected to the heel 30 and to conductive insert 37 in insulating plug 38 held therein. The said plug is located within the open end of the heel and forms part of the support for holding pins 39 which protrude laterally from the said heel. When used in a projector such as that shown in Fig. 5, the heel functions like a bayonet type lamp base as it fits snugly within the tubular portion 40 of a socket which carries the usual spring pressed contact pin (not shown) which engages center contact 37. The pins 39 engage bayonet slots 41 in the socket shell. The projector housing 42 supports the socket which connects to contacts carried by cap 43 connected to conductors in cord 44. The projector is also preferably covered by a lens 45 which has an attaching ring 46.

What we claim as new and desire to secure by Letters Patent of the United States, is:

In a light projector, the combination of an electric lamp comprising a concentrated light source and an enclosing bulb, a reflector comprising a heel portion which is fixedly united to the neck of said bulb, and terminal connections supported by said heel portion, said light source being accurately located with reference to said reflector to produce a beam of desired dimensions and direction.

VAL J. ROPER.
